(57) **CLAIM**

An ornamental design for an electric circular saw with a safety guard, as shown and described.

DESCRIPTION

FIG. 1 is a perspective view of the electric circular saw with a safety guard with the blade in a raised condition showing my new design;

FIG. 2 is a front view of FIG. 1 with the blade in lowered condition;

FIG. 3 is a rear view of FIG. 2;

FIG. 4 is a left side view of FIG. 2;

FIG. 5 is a right side view of FIG. 2;

FIG. 6 is a top view of FIG. 2;

FIG. 7 is a bottom view of FIG. 2;

FIG. 8 is another view of FIG. 1 showing a cylinder clamped onto the platform;

FIG. 9 is a front view of FIG. 1; and,

FIG. 10 is a rear view of FIG. 1.

The broken lines showing environment in the drawings are for illustrative purposes only and form no part of the claimed design.
